UNITED STATES PATENT OFFICE.

HERBERT NAPIER PRENTICE, OF STOWMARKET, ENGLAND.

ELECTRIC CUT-OUT.

SPECIFICATION forming part of Letters Patent No. 504,938, dated September 12, 1893.

Application filed May 31, 1893. Serial No. 476,092. (No model.) Patented in England April 12, 1889, No. 6,284.

To all whom it may concern:

Be it known that I, HERBERT NAPIER PRENTICE, electrician, a subject of the Queen of Great Britain and Ireland, residing at Stowmarket, in the county of Suffolk, England, have invented certain Improvements in Electric Cut-Outs, (for which I have obtained a patent in Great Britain, No. 6,284, dated April 12, 1889,) of which the following is a specification.

The object of my invention is to provide a cut-out for electric circuits which is simple in construction and very efficient and certain in action.

15 The invention relates to the class of cut-outs which are operated or caused to operate by variation in magnetic attraction due to an abnormal condition of the current in the circuit to be controlled.

20 According to my invention I cause the armature which is attracted or relieved from the attraction by the magnetic coil or core (wound with wire included in or taken as a shunt from the circuit to be governed) to actuate a tumbler or kicker so that the said tumbler or kicker being overbalanced or released falls and acts on the bridge or contact makers to quickly and with certainty remove it or them from the mercury cups or contacts.

25 The kicker or tumbler or some part operated when the circuit is broken I prefer to arrange as an annunciator to clearly indicate to the attendant that the breaking of the circuit has taken place.

30 In order that my said invention may be fully understood I shall now proceed to describe the best means with which I am acquainted for carrying it into effect and for that purpose shall refer to the annexed drawings.

40 Figure 1 is a side view and Fig. 2 is a front view of a cut-out constructed or arranged according to my invention showing the parts in the positions they occupy when the circuit is complete. Fig. 3 is a side view showing the 45 parts in the position which they assume when the circuit is broken. The arrangement here shown is one in which the circuit is broken when the current exceeds a predetermined limit. A is the core of the electro magnet 50 wound with wire included in or taken as a shunt from the circuit to be controlled b b² being the sockets or binding screws by which

the external wires are secured. The said sockets or screws are on conducting pieces B B² the piece B² being electrically connected 55 to the conducting piece B³ carrying the mercury cup C² and the piece B being in electrical connection through the coil of the electro magnet with the conducting piece B⁴ carrying the mercury cup C. Into the cups C C² 60 dip the ends d of the bridge piece D provided with arms d² centered by the pin e to the bracket f. On this pin e are also centered the arms g carrying the armature g² the said arms being connected by the cross piece g³ extending 65 behind the lever H also centered on the pin e and having a counter balance weight at h and a tail piece h² constituting a kicker. I is a screw in the bracket i by means of which the position of the armature g² relatively to 70 the end of the magnet core A can be adjusted. The parts are mounted on a support or base X of insulating material. When the current is in the proper normal condition the parts remain in the position shown in Figs. 1 and 2 75 but on the current increasing to such an abnormal extent as to cause the electro magnet to attract the armature g² the cross piece g³ moves the lever H into such a position that its weighted head h causes it to suddenly fall 80 over so that its tail end h² kicks the bridge and knocks it over into the position shown in Fig. 3 quickly removing the contacts d from out of the mercury cups and breaking the circuit. The inner part x of the lever H may be colored red or otherwise colored or marked so 85 as to act as a readily observable annunciator of the breaking of the circuit.

Figs. 4, 5, and 6 are views corresponding to Figs. 1, 2 and 3 showing the arrangement 90 when the apparatus is to be used to break the circuit when the circuit falls below a predetermined limit. In these figures the parts which correspond with those shown in Figs. 1, 2 and 3 are marked with the same letters 95 of reference. The armature in this case is held in the position in which the circuit is completed by the core attracting the armature. When the current lessens to a point at which the attractive power of the core is insufficient 100 to maintain the armature in position it falls over and the parts operate as hereinbefore described.

When the apparatus is used for continuous

currents I prefer to use a core to the magnet as shown but when the apparatus is used for alternating currents I prefer to dispense with the core or to use a core made up of insulated iron wires or plates.

I claim—

1. In a magnetic cut-out, the combination with the magnet the armature and the contact pieces, of a pivoted arm having a weight on one end normally opposing the action of the magnet and initially moved by the armature when the current becomes abnormal, and having the other end arranged to kick the contact pieces as the weight falls, where-
5 by the contact is broken, substantially as described.
2. In a magnetic cut-out, the combination with the magnet, the armature and the contact pieces, of a pivoted arm having a weight on one end normally opposing the action of the magnet and initially moved by the armature when the current becomes abnormal,
10
- 15
- 20

and having the other end arranged to kick the contact pieces as the weight falls, with an adjusting screw adapted to regulate the 25 distance between the armature and the magnet, substantially as described.

3. In a magnetic cut-out, the combination with the magnet and contacts, of a slotted armature, a weighted arm having a tail piece 30 for removing the contact piece, the said weighted arm journaled on the same axis with the armature, and within the slot thereof, substantially as described.

In testimony whereof I have signed my 35 name to this specification in the presence of two subscribing witnesses.
